PIRN FOR LOOMS

Application filed September 12, 1929, Serial No. 392,219, and in Switzerland September 20, 1928.

This invention is intended to permit a sufficient braking of the weft thread winding of a pирн for automatic silk-weaving looms which passes through the centre-bore of the 5 pирн.

It has been found that a thread which is braked on the periphery of the pирн and passed thereupon through the centre-bore of the pирн affords no satisfactory braking 10 effect. This disadvantage is overcome by the present invention which provides a braking device in the centre bore of the pирн.

In the drawings:

Fig. 1 is a longitudinal section of the improved pирн,

Fig. 2 is a cross-section on the line *a—a* of Fig. 1 and

Fig. 3 is an elevation of the pирн.

In Figs. 1, 2 and 3, 1 is a pирн through the 20 central bore 3 of which runs the weft thread 2 winding off the pирн. In the centre-bore 3 of the pирн a braking device 4 is inserted. The device may be pelt. The weft thread passing through the hairs of the pelt is suit- 25 ably braked in the centre-bore of the pирн.

What I claim is:

1. A pирн for automatic silk weaving looms having a center bore serving as a thread 30 guide, and a braking device inserted in the center bore of the pирн consisting of felt, said braking device being engageable with the thread passable through the bore.

2. A weft pирн for automatic silk weaving looms having a center bore serving as a 35 weft thread guide, and a braking device inserted directly in the center bore intermediate the ends thereof, said braking device being engageable with the weft thread passable through the bore.

40 In testimony whereof I have affixed my signature.

ERNST EGGLI.
